ABSTRACT OF THE DISCLOSURE

An electrically illuminated educational toy takes the form of a hollow die. A light bulb is provided in a discrete compartment behind each face, and the die encloses a battery and conductive means for causing only the die face which is on top to be illuminated in any at rest position of the die. The bulbs may be distinctively colored and each die face desirably has printed on it the name of the color which it displays.

A composite mercury switch, located within the die, constitutes a distinctive feature of the invention.

This invention relates to electrically illuminated game apparatus, and more particularly to self-contained, self-energized circuits, including color differentiated electric lights therefor, such that the color of the illumination will depend upon the position or attitude in which the apparatus comes to rest upon a level surface.

It is an object of the invention to provide a hollow die having translucent faces, marked respectively, "red," "orange," "yellow," "green," "blue" and "purple," with a light of the named color mounted behind each face in a closed compartment, the construction and arrangement being such that the placing of a die on a level surface in any attitude will always cause the top face to be illuminated by a light of the color named on the top face.

To the foregoing end, it is an important feature that a simple, inexpensive, rugged and dependable, composite mercury switch is provided within the die, consisting of a common enclosure in which a single, limited quantity of mercury is contained, the enclosure providing a multiplicity of evenly distributed switch wells or depressions, one for each light, into any one of which wells the mercury may flow, with each well including a pair of switch terminals which are adapted to be connected by the mercury in series with a common source of electrical potential and with a single associated light.

It will be readily evident, of course, that two or more dice of the kind referred to could be used for playing various games, such as Monopoly, Parcheesi, Skunk, etc., that the faces of the dies may be numbered according a a uniform scheme of color and number association, and that any regular polyhedral die form (excepting the tetrahedron) may be used.

The composite mercury switch is regarded per se as an important invention, capable of serving advantageously and effectively for many purposes other than the illumination of game apparatus.

Other objects and advantages will hereinafter appear. In the drawing forming part of this specification,

FIGURE 1 is a perspective view of a hollow, translucent die shell which is employed in one practical and advantageous illustrative structure embodying features of the invention;

FIGURE 2 is a plan view of an assembly of generally similar wall units or panels, which fits snugly within the shell of FIGURE 1 but in which only the top panel is seen;

FIGURE 3 is a view in sectional elevation of the assembly of FIGURE 2, the section being taken on the longi-

2

tudinal central vertical plane of FIGURE 2, looking toward the left;

FIGURE 4 is a horizontal, sectional view taken on the line 4—4 of FIGURE 3, looking in the direction of the arrows;

FIGURE 5 is a fragmentary detail sectional view on a greatly enlarged scale as compared with the other figures, showing how the removable cover portion of the shell is releasably retained in closed position; and

FIGURE 6 is an electrical diagram showing the parallel disposition of the several lights and their respective switches, and their series relation to a common battery and an associated master switch.

In FIGURE 1 disclosure is made of a partially open die shell 10, composed of a top removable cover marked "RED—1," and a hollow five-sided cubical tray 12, having its sides marked respectively, "ORANGE—2," "YELLOW—3," "GREEN—4," "BLUE—5," and "PURPLE—6". The numbers appearing on opposite faces of the shell add to seven in every instance, as in an ordinary die. The cover 1 and the tray 12 are separately molded, to provide thin, translucent walls. The walls are desirably composed of a strong, resilient, substantially rigid, inflexible plastic material, such as polystyrene. The bottom wall 6 is a complete, unbroken square. The side walls 3, 4 and 5 are of the same area and shape as the wall 6, but are provided along their inner upper margins with undercut grooves 14 for slidingly receiving and retaining the cover 1. The cover is formed with bevelled side

20 and rear upper margins which fit in the side and rear wall grooves, but its front boundary is disposed at right angles to its outer and inner surfaces, to coincide with the outer face of the wall 2 when the cover is closed, as shown in FIGURE 5. The cover 1 latches shut in the fully closed position, but may be conveniently opened for affording access to the interior of the shell. A small shouldered hump 16, provided on the lower face of the cover near the front end of the cover, snaps behind the wall 2 to hold the shell closed. A finger nail recess 18 is provided in the lower face of the cover just over the upper boundary of the wall 2, so that the cover may be deformed sufficiently to cause the hump 16 to clear the wall 2, and a small recess 20 is provided in the upper surface of the cover to assist in sliding the cover open.

25 30 35 40 45 50 55 60 65 70

A hollow structure composed of six generally similar molded panels 22, 24, 26, 28, 30 and 32 is adapted to be assembled and fitted within the shell 10, the top panel 22 being put into place in the shell last, after an interior composite mercury switch 34 has been secured in place and all wiring has been completed.

The panels 26, 28, 30 and 32 are identical, while the panels 22 and 24 differ in minor details. The panel 28, for example, has relatively narrow top and bottom marginal portions 35 and 36 and a recessed reflector portion 38 which protrudes inward beyond the inner boundary of the marginal portions. The marginal portions of the panels are flat and are disposed in coplanar relation, being adapted to bear continuously against marginal areas of the associated face or wall of the shell. Each of the panels 26, 28, 30 and 32 has one wide vertical margin 40 and one narrow vertical margin 42. In each instance the sum of the width of the narrow margin 42 and the standard thickness of a margin is equal to the width of a wide margin 40, as is clearly evident from an inspection of FIGURE 4.

It will be noted that each reflector recess is shown as arcuate in cross-section but square in plan. This kind of surface can be best explained by explaining the structure of a mold surface suitable for producing it. Such a mold surface would be produced by cutting horizontally through a solid, horizontally disposed cylinder at right angles to

the axis thereof, using a circular saw of the same diameter as the cylinder. The reflector recess is complementary to a segment of the resulting surface. The described and illustrated form of reflector recess is only one of many forms which would be suitable.

The reflector surface is desirably highly reflective in character, but is designed to include a multiplicity of minute irregularities so that there will be diffuse reflection throughout. At the center of each reflector recess a light socket 44 is mounted. A light bulb 46 of appropriate color is mounted in each socket.

It will be noted that each light bulb is contained in a discrete compartment of substantial depth, formed jointly by a shell wall and an associated panel.

The panels 22 and 24 have wide marginal portions on all four sides. The four marginal portions of the panel 24 are solid, however, while the panel 22 is formed with a recess 48 of substantial length, width and depth in the upper surface of its rear marginal portion.

Two dry batteries 50 and 52 and a small on-off master switch 54 of any suitably compact character are lodged in the recess 48. The batteries are desirably placed bottom to bottom with a conductive spring interposed between them and connected to a conductor 56. The positive center terminals of the batteries are connected through wires 58 and 60, respectively, to the input side of master switch 54. The two batteries are connected in parallel relation in order to avoid frequent renewal of the batteries, but the precise battery arrangement is just a detail which may be varied as desired. The slidable cover section 1 is provided for access to the master switch 54, and for convenient replacement of the batteries—also for access to the interior of the panel-formed enclosure when required.

Before the panel enclosure is completed within the shell 10 by the putting in place of the top panel 22, the composite mercury switch 34, which forms a very significant feature of the invention, is installed and connected in circuit with the lights and the batteries. The composite switch 34 in the illustrative form comprises a rigid hollow sphere 61 of non-conductive, plastic material, having six protruding mercury switch wells 62, 64, 66, 68, 70 and 72. These wells are symmetrically and evenly spaced, each being separated by ninety degrees from each of the four nearest wells, and diametrically opposite the remaining well. The sphere 61 includes four external mounting bosses 74 quadrangularly spaced from one another in the horizontal great circle plane. Each boss 74 is recessed to receive snugly the inner end of a supporting rod 76, and each supporting rod, in turn, is carried by a corner post 78. (See FIGURE 4.) Each rod 76 is screwed deeply into the associated corner post 78 for insertion into the panel-bounded enclosure, but after insertion the rod is manually unscrewed partway from the post for insertion into the associated boss 74. When the sphere 61 has been snugly secured in place by the four rods 76, with the center of the sphere in substantial or exact coincidence with the geometrical center of the die, lock nuts 80, threaded on the respective rods, are screwed into firm engagement with the respective, associated corner posts 78.

As installed, each of the wells 62, 64, 66, 68, 70 and 72 has two insulated wires connected to it with bared ends of the wires extending into the well for engagement with the mercury on occasion, but with the two wires definitely out of contact with one another. (See FIGURE 3.) In each instance one of these two wires is a black or hot wire 82. Each wire 82 connects one of the wells electrically with a black main conductor wire 94. The wire 94 is connected through master switch 54 with the batteries 50 and 52.

The other wires connected into the wells 62, 64, 66, 68, 70 and 72, designated 102, 104, 106, 108, 110 and 112, respectively, may desirably be red, purple, green, yellow, orange and blue, respectively, and are connected to the correspondingly colored electric lights which are 75

carried by the panels 22, 24, 26, 28, 30 and 32. The red, purple, green, yellow, orange and blue lights are connected through individual white conductors 122 to the common white conductor 56, and through the latter to the negative terminals of the battery.

In order to avoid confusion, only stubs of the various wires connected to the lights and to the mercury switch wells are shown in FIGURES 3 and 4, and only the colored wires which run from the switch wells to the lights are identified by reference characters. The complete wiring arrangement is shown, however, in FIGURE 6. It will be noted that each mercury switch well controls the illumination of the opposite side of the die from that at which the well is located; that is to say, the well switch which happens to be at the bottom, will cause energization of the light for the die face which happens simultaneously to be at the top. This requires only that the colored wires which form built-in parts of the mercury switch assembly be color-matched with the lights installed in the various panels.

In FIGURE 3 a small body of mercury 134 is shown contained in the bottom well 62 for illuminating the red light carried by the top panel 22. As the die is rolled or turned from side to side, this same small body of mercury, confined within the sphere 61, runs from well to well, closing the other circuits selectively. Since mercury has a density of 13.6 and presently costs in the neighborhood of six dollars per pound, the use of a single small quantity to function in any one of a multiplicity of switch wells 30 effects an important economy.

The educational toy illustrated and described is attractive to very young children, and may be used for familiarizing them with the primary and secondary colors, for teaching them the names of those colors, for teaching them 35 to read the names, for teaching them the thirteen letters of the alphabet included in those names and the numbers from one to six, inclusive, and for teaching them the order of occurrence of the colors in the solar spectrum or rainbow.

In an older age group, extending up into the teens and even into adulthood, a pair of dice of the kind disclosed herein can be very useful and attractive for playing various games. Association of the colors with the numbers is soon memorized so that the color helps to identify the number for all contestants and tends, therefore to eliminate disputes. The colors can be noted and differentiated from angles and at distances which might make the numbers indistinct or unreadable.

As an alternative to the employment of colored light 50 bulbs the inner face of each shell wall may be lined with a light shield of the distinct color characteristic of that face. In all other respects the structure could remain as described above.

I have described what I believe to be the best embodiments of my invention. I do not wish, however, to be confined to the embodiments shown, but what I desire to cover by Letters Patent is set forth in the appended claims.

I claim:

- 60 1. Game equipment consisting of
  - (a) a hollow die substantially in the form of a regular polyhedron having more than four faces, so that any given face has a parallel face directly opposed to it which will be on top when the given face rests on a level surface, each face being marked in a distinctive manner,
  - (b) means cooperative with the faces to provide substantially closed, discrete compartments, one immediately behind each face,
  - (c) an electric light bulb in each compartment,
  - (d) a battery within the die,
  - (e) a composite mercury switch within the die consisting of
    - (e1) a completely closed hollow body having a mercury collecting well opposite each face of the

- die and otherwise free from mercury collecting irregularities;
- (e2) a pair of conductive switch contacts disposed in spaced relation within each well,
- (e3) a single body of mercury within the hollow body, adapted to flow from well to well and sufficient in quantity, at least, to wet the contacts in whichever well is lowermost when the die is at rest on a level surface, and
- (f) conductive means constructed and arranged selectively and individually to connect each light, when uppermost, in series with the switch closing mercury in the opposite or lowermost well and with the battery, so that any uppermost face of the die will alone be lighted when the die stands at rest on a level surface.
2. Game equipment as set forth in claim 1 in which each face of the die when lighted has a characteristic color distinct from that of any of its immediate neighbors, and in which at least six distinctive face colors are provided.
3. Game equipment as set forth in claim 2 in which the distinctive color of each die face is provided by making the associated light bulb of that color.
4. Game equipment as set forth in claim 3 in which the distinctive marking on each face includes at least the name of its color.
5. Game equipment as set forth in claim 1 in which a battery protective master switch is provided in series with the battery for rendering the composite mercury switch active and inactive at will.

6. Game equipment as set forth in claim 5 in which the die is in the form of a cube.

7. Game equipment as set forth in claim 6 in which the die includes a hollow shell of translucent material which forms the several die faces with one face or wall of the shell removably held in place, so that access can be had through removal or partial removal of said wall to the battery and to the master switch.

8. Game equipment as set forth in claim 7 in which the means cooperative with the die faces to form discrete compartments consists in the case of each compartment of a panel having co-planar, flat marginal areas continuously engageable with margins of the associated shell wall, and an external concave area of substantial depth.
